United States Patent Office

Des. 213,089
Patented Jan. 7, 1969

213,089

BOTTLE

Howard Ross Justice II, 830 SW. 2nd St.,
Boca Raton, Fla. 33432

Filed Apr. 24, 1967, Ser. No. 6,797

Term of patent 3½ years

U.S. Cl. D9—64
Int. Cl. D9—01

FIG. 1

FIG. 2

The dominant features of my design reside in the portions shown in full lines.

I claim:

The ornamental design for a bottle, as shown and described.
